UNITED STATES PATENT OFFICE

140,638

DESIGN FOR A HOUSE SLIPPER

Gustave Cohn, Hartsdale, N. Y.

Application October 4, 1944, Serial No. 115,601

Term of patent 3½ years

(Cl. D7—7)

To all whom it may concern:

Be it known that I, Gustave Cohn, a citizen of the United States and a resident of the town of Hartsdale, in the county of Westchester and State of New York, have invented a new, original, and ornamental Design for a House Slipper, of which the following is a specification, reference being had to the accompanying drawing, forming a part thereof.

Fig. 1 is a perspective view of a house slipper showing my design.

Fig. 2 is a bottom view thereof.

I claim:

The ornamental design for a house slipper, substantially as shown.

GUSTAVE COHN.
